Letter Patent

The schedule referred to in their Letter Patent and making
part of the same, containing a description in the words of
the said Joseph Hibbard and John B. Cattin & Thomas G. Abell
themselves, of their improvement in the cooler for cooling flour and
separating the coarse bran before the flour passes into the batter
called Hibbard, Cattin and Abell improved cooler
to all to whom these presents shall come

Joseph Hibbard, John B. Cattin & Thomas G. Abell of
Pompei in the County of Chautauque and State of New
York send Greeting

Be it known that we the said Joseph Hibbard, John B.
Cattin & Thomas G. Abell have invented, constructed, made
and applied to use a new and useful cooler for cooling
flour, and separating the coarse bran from the flour while
in the operation of cooling and before the flour passes into
the batter called Hibbard, Cattin and Abell improved
cooler, and the following is a full and exact description of
the same as invented by us. The improved cooler consists
of a rolling screw or shaking sive which receives the ground
grain or meal from the elevators by means of a common
conveyor instead of having it conveyed to hopper boys or
usually the case the conveyor which receives the meal from
the elevators and conveys it into the sive, the spout which
conveys the coarse bran from the sive, conveyor which con-
veys under the sive and receives the meal after it is
separated from the coarse bran and conveys it back and
forth through the machine a sufficient number of times

to cool it (in the one now in use once only) a spout which receives the meal from the end of the last conveyor, & through which it falls into the hoppers, and a case which covers the whole except the first conveyor, with standing sides to direct the meal which falls, or is sifted through the screen into the last conveyor 1. The screen is made after the manner of a common roller with six sides and is composed of or covered with iron wire of a proper texture to retain the coarse bran, and to permit the rest of the meal to pass or be sifted through it. The screen rolls with the shaft to which it is attached and which according to the above description composes a part of the machine which we call the screen. On one end of the shaft is a common conveyor which receives the meal from the elevator, and by its rotary motion conducts it within the screen whence by the same motion it is sifted through the screen, except the coarse bran which is carried throughout the whole length of the screen and discharged into a spout at the opposite end from that into which it was received. The screen now used by us is eight feet long and twenty six inches in diameter and made of or covered with iron wire, but the length and diameter may be varied according to circumstances, and it may also be made of or covered with any other suitable material than iron wire though we now know of nothing better. 2. The conveyor which receives the meal from the elevator and which is the end of the shaft on which the screen turns, runs in an appropriate spout or case and is about three feet long but its length may be varied according to circumstances. It must be sufficiently long to reach from the elevator into the screen and deposit the meal there. The said screen and conveyor are placed nearly horizontal having a sufficient inclination to give proper to the meal which is received at one end of the screen.

from the conveyor, and to discharge the coarse bran into a spout at the opposite end at common bottles, operate or
9. A. Directly under the screen is another conveyor made in the common form of the same length of the screen, into which the meal which is sifted through the screen falls, being directed by two boards of the same length and of proper width placed horizontally and parallel to each other, the lower edges of which meet and are worked so as to make a track for it to direct or guide all the meal through the conveyor, and the upper edges of which are far enough apart to receive all the meal which is sifted through the screen. From the lower end of this conveyor the meal falls into a screen having an opposite direction & made in the same manner, and from the inclined end of this it falls into a third, having an opposite inclination to the last and made in the same manner; and from the inclined end of this third conveyor is a spout which receives the meal and conducts it into the bottle. The meal after being separated from the coarse bran (which is done while warm) is thus carried through the whole length of the machine by the three sets of conveyor for the purpose of rendering it perfectly cool before entering the bottle. Any number of conveyor may be used as may be necessary and convenient. An ordinary Mills one is sufficient and the length of the screen and conveyor under meat may be increased so as to have one conveyor sufficiently cool the flour in all cases. Those now in use have one conveyor under the screen only and from six to eight feet in length as above mentioned, — This size and length with one conveyor underneath only is sufficient for two bins of flour. Attention is given to the screen and conveyor by such kinds of gearing or machinery as the constructor shall prefer, so as is commonly used in such cases. 4. The screen and conveyor or conveyor underneath are covered with an inclined in a case, (with sufficient opening to admit the air) to screen the meal, from the dust and filth of a stable, and from any current of wind that may blow it.

way or waste it; The whole is surrounded with this set of con-
-veyors by a mould made in a screen sufficiently large, beneath
transmitted and a drawing conserto answered. The benefits
and advantages of the above invention are principally the
following 1. It saves the expence of hopper boys and the ap-
-paratus to conduct the meal to and from them as made in the
usual way. 2. It saves some expence in making the coarse
end of the batter which is nearly equal to the cost of the
improved cooler. 3. by taking out the coarse bran before
the meal passes into the batter from one to three pounds of
flour is procured from each bushel of wheat more than is pro-
-duced in the usual way is probably prevented from being sifted
through the batter by the coarse bran or adheres to the coarse
bran in its passage through the batter. 4. By separating
the coarse bran from the flour before it passes into the batter
it saves the batter from the friction and wear finer the coarse
bran. — In testimony that the above is a true specification
of our said improvement as above described we have hereunto
set our hands and seals the seventeenth day of February eighteen
hundred and thirty five —
